[57] CLAIM

The ornamental design for a hydrotherapy spa, as shown.

DESCRIPTION

FIG. 1 is a top perspective view of the hydrotherapy spa showing our new design;
FIG. 2 is a front elevational view of the hydrotherapy spa shown in FIG. 1;
FIG. 3 is a top plan view of the hydrotherapy spa shown in FIG. 1;
FIG. 4 is a cross-sectional view taken along the line 4—4 of FIG. 3;
FIG. 5 is a left side elevational view of the hydrotherapy spa shown in FIG. 1; and
FIG. 6 is a rear elevational view of the hydrotherapy spa shown in FIG. 1.
